(57) **CLAIM**

The ornamental design for a smart-key, as shown and described.

DESCRIPTION

FIG. 1 is a front and top perspective view of a smart-key with a connection component;

FIG. 2 is a top view thereof;

FIG. 3 is a bottom view thereof;

FIG. 4 is a front view thereof;

FIG. 5 is a rear view thereof; and,

FIG. 6 is another front and top perspective view thereof. The broken lines depict environmental subject matter only and form no part of the claimed design.

1 Claim, 6 Drawing Sheets**FIG. 1**

FIG. 2

FIG. 3

FIG. 4

FIG. 5

FIG. 6
